UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

TRANSITION CAR-COUPLING.

1,333,317.

Specification of Letters Patent.

Patented Mar. 9, 1920.

Application filed April 11, 1918. Serial No. 227,839.

To all whom it may concern:

Be it known that I, WILLIAM KELSO, a citizen of the United States, residing at Pittsburgh, in the county of Allegheny and 5 State of Pennsylvania, have invented certain new and useful Improvements in Transition Car-Couplings; and I do hereby declare the following to be a full, clear, and exact description of the invention, such as 10 will enable others skilled in the art to which it appertains to make and use the same.

My invention relates to the construction of transition car couplings enabling cars equipped therewith to be readily coupled 15 either to cars having couplings of the European hook type or to cars having couplers of the Master Car Builders type, as well as to cars equipped with similar transition couplings. During the period when couplings of the hook type are being gradually 20 supplanted by couplers of the M. C. B. type, a form of transition coupling that will couple with both of the other types must be employed, and, for obvious reasons of economy, it is desirable that such transition 25 couplings shall be of a character rendering them readily convertible into typical M. C. B. couplers after the necessity for transition couplings is past.

The principal object of the invention is 30 to provide a conveniently manipulated and efficient transition coupling which may be readily assembled and disassembled. A further object of the invention is to so combine 35 the M. C. B. coupler mechanism and the auxiliary coupling devices for coöperating with the hook coupling of the European type that pulling strains communicated to the M. C. B. coupler elements from the aux- 40 illary coupling devices may be distributed and equalized so as to maintain a central or substantially central draft upon the M. C. B. coupler.

Generally stated, these objects are accom- 45 plished by movably securing to the head of an M. C. B. coupler a transversely extending equalizer bar bearing at its center a horizontally rotatable link which is adapted to be connected to a hook coupling of the 50 European type, the equalizer bar being detachably interlocked to the means for connecting it to the coupler head in such manner that these parts can only be disconnected when the equalizer bar is in an abnormal 55 position.

In the drawings illustrating the preferred form in which I have contemplated applying the principle of my invention, the scope whereof is pointed out in the claims,

Figure 1 is a plan view of a transition car 60 coupling embodying the invention.

Fig. 2 is a side elevation of the mechanism shown in Fig. 1, the auxiliary coupling device being in coupling position.

Fig. 3 is a view in side elevation, illustrating the position to which the parts are brought when effecting the dissociation of the auxiliary coupling device from the M. C. B. coupler mechanism.

Fig. 4 is a detail front elevation of the 70 equalizer bar of the auxiliary coupling device.

The transition car coupling involves an M. C. B. coupler having a head 1, a knuckle 2 pivotally mounted thereon, and a lock 3 75 for retaining the knuckle in closed position when the M. C. B. coupler is used to couple with another coupler of the same type. A well known form of M. C. B. coupler is illustrated in the drawings; but, except as hereinafter claimed in particular combinations of parts, the details of construction of the elements constituting the M. C. B. mechanism may be of any suitable or ordinary construction.

As a means for movably connecting to the coupler head 1 the coupling device by which the car may be coupled to another car equipped only with a coupling of the European type, the coupler head is preferably 90 formed with oppositely disposed laterally projecting hooks 4 whose bights open toward the rear. The hooks 4 respectively extend through corresponding eyes 5 formed at the rear ends of link members 6 which are movably connected at their forward ends to the outer ends of a transversely extending equalizer bar 7. For the purpose of forming a connection with the equalizer bar the link members 6 are preferably provided at their forward ends with eyes 8, similar to the eyes 5, and the equalizer bar 7 is formed with hooks 9 adapted to coöperate therewith. When the parts are in the positions occupied in making a coupling 105 with a hook coupling of the European type the hooks 4 and 9 face in opposite directions, thereby preventing the device from becoming accidentally disassembled; but, as will be readily understood upon refer- 110

ence to Fig. 3 of the drawings, the parts nevertheless may be readily detached from each other for the purpose of repairing or renewing worn or damaged members by simply swinging the equalizer bar 7 upwardly and rearwardly until the hooks 4 and 9 are parallel. In this relation of the hooks the link members 6 may be rotated on their longitudinal axes and disconnected.

10 The transversely extending equalizer bar 7, which in coupling position stands in advance of the knuckle 2 of the coupler bears at its center means adapted to be connected to the hook of a European type coupling, such means preferably consisting of a link 10 entering a slot 11 in the equalizer bar and pivotally connected to said bar by a pivot pin 12. The link 10 is thus capable of swinging in a horizontal plane from side to side and also of sliding rearwardly, thereby being able to pull centrally on the equalizer bar when the car is passing around a curve and to allow the coupled cars to approach and recede from each other in consonance with the movements of the opposed buffers on the connected cars. To permit extended rearward sliding of the link 10 the outer end of the knuckle 2 is formed with a centrally disposed horizontal slot 13 adapted to receive the rear end of the link. As shown in Figs. 1 and 4 the slot 11 in the equalizer bar is preferably flared forwardly, and as illustrated in dotted lines in Fig. 1 the wall of the knuckle at the base of the slot 13 preferably slopes from the rear forwardly away from the longitudinal axis of the coupler head 1, provision being thereby made for free pivotal movement of the link 10 under all usual conditions of service.

When not in use for coupling cars together the auxiliary coupling devices by which connection with a hook coupling is effected hang vertically from the hooks 4 on the sides of the coupler head. In this position the auxiliary hook coupling devices do not interfere with the use of the M. C. B. coupler mechanism.

I claim:

1. In a device of the character indicated, the combination with a coupler head, of an equalizer bar, means attached to said equalizer bar for connecting the latter to a hook coupling of the European type, and means for movably connecting said equalizer bar to the coupler head to permit horizontal and vertical movements of said bar, said last named means involving a plurality of spaced members connected to said equalizer bar on opposite sides of the means for connecting the equalizer bar to said hook coupling.
2. In a device of the character indicated, the combination with a coupler head, of a transversely extending equalizer bar, means for connecting the equalizer bar to the

coupler head to permit horizontal and vertical movements of said bar, and means for connecting the equalizer bar to a hook coupling of the European type.

3. In a device of the character indicated, the combination with a coupler head having oppositely extending hooked lugs, of an equalizer bar provided with spaced hooks, means respectively engaging the hooks of said equalizer bar and the corresponding hooked lugs of said coupler head to thereby attach said equalizer bar to said head, and means for connecting the equalizer bar to a hook coupling of the European type.

4. In a device of the character indicated, the combination with a coupler head having rearwardly turned hooks, of an equalizer bar having forwardly turned hooks, and link members each formed with eyes respectively receiving one of the hooks of said equalizer bar and the corresponding hook of the coupler head.

5. In a device of the character indicated, the combination with a coupler head having oppositely disposed hooks, of an equalizer bar provided with hooks, said hooks on the coupler head and equalizer bar normally facing in opposite directions, and means detachably engaging corresponding hooks of the coupler head and equalizer bar for connecting said head and equalizer bar.

6. In a device of the character indicated, the combination with a coupler head, of an equalizer bar, and means interlocking with and detachably connecting said coupler head and equalizer bar, said equalizer bar being adapted to be disconnected from said means only when displaced from normal position.

7. In a device of the character indicated, the combination with a coupler head, of a transversely extending equalizer bar, means for movably connecting the equalizer bar to the coupler head to permit horizontal and vertical movements of said bar, and means movably connected to the equalizer bar for connecting the latter to a hook coupling of the European type.

8. In a device of the character indicated, the combination with a coupler head, of an equalizer bar, means for movably connecting the equalizer bar to the coupler head, and a link pivotally mounted on said equalizer bar and capable of swinging laterally from side to side, said link being adapted to slide rearwardly with respect to said equalizer bar.

9. In a device of the character indicated, the combination with a coupler head, of a transversely extending equalizer bar disposed in advance of said head when in coupling position, horizontally and vertically movable link members engaging said equalizer bar on opposite sides of its center and connecting it with the coupler head, and a link member movably mounted on said equalizer bar at the center thereof.

10. In a device of the character indicated, the combination with a coupler head, of an equalizer bar having a slot intermediate of its ends, means for movably connecting said equalizer bar to the coupler head, a link extending into the slot in the equalizer bar, and means for permitting said link to execute a pivotal movement with respect to said equalizer bar.
11. In a device of the character indicated, the combination with a coupler head, of a knuckle having a horizontally slotted outer end, an equalizer bar disposed in advance of

said head when in coupling position, means for movably connecting said equalizer bar 15 to the coupler head, and means mounted on said equalizer bar for connecting the latter to a hook coupling of the European type, said last named means being in horizontal alinement with the slot in the outer end of 20 the knuckle and being adapted to move rearwardly with respect to the equalizer bar and enter said slot.

In testimony whereof I affix my signature.

WILLIAM KELSO.
